UNITED STATES PATENT OFFICE.

NORMAN McCARTY, OF INDIANAPOLIS, INDIANA, ASSIGNOR TO ATLAS ENGINE WORKS,
OF INDIANAPOLIS, INDIANA, A CORPORATION OF INDIANA.

GOVERNED PUMP.

943,095.

Specification of Letters Patent. Patented Dec. 14, 1909.

Application filed August 9, 1909. Serial No. 511,985.

To all whom it may concern:

Be it known that I, NORMAN McCARTY, a citizen of the United States, residing at Indianapolis, in the county of Marion and State of Indiana, have invented certain new and useful Improvements in Governed Pumps, of which the following is a specification.

The object of my invention is to produce a pump capable of delivering variably measured quantities of a fluid, and of such character that no material pressure will be exerted upon the mechanism by means of which the amount of delivery is varied, thus making a pump which is especially adapted for use in delivering successively measured, variable quantities of liquid fuel to an internal combustion engine of the non-explosive type, the adjusting mechanism of the pump being connected with a speed controlled governor driven by the motor.

The accompanying drawing, which is a vertical section, illustrates an embodiment of my invention.

In the drawing, 10 indicates a suitable pump body having a pump chamber 11 formed therein. Projected into chamber 11, through a suitable packing gland 12, is a displacing plunger 13 which may conveniently have a uniform stroke produced in any desired manner, as, for instance, by means of the arm 14 carried by strap 15 surrounding an eccentric 16 carried by shaft 17. Leading into chamber 11 is a supply pipe 18 in which is arranged the usual inwardly opening check valve 19, and leading from chamber 11 is a discharge pipe 21 in which is mounted the usual outwardly opening check valve 22. Also projected into chamber 11, through a suitable packing gland 23, is a compensating plunger 24. Plunger 24 at its outer end, is formed into a plunger 25 which passes through a suitable packing gland 26 into a pressure chamber 27 into which is introduced, through a suitable pipe 28, a yielding fluid pressure of sufficient amount to propel plunger 24 through the packing of gland 23 when plunger 13 is being retracted.

Plunger 24, in its outward stroke, needs to be definitely and uniformly limited, and any desirable stop may be adopted for this purpose. Probably the most convenient construction however is to provide a shoulder 31 in chamber 27 against which the end

of plunger 25 will be driven and thus limit the outward movement of plunger 24.

In order to vary the suction effect of plunger 13 upon the contents of supply pipe 18, an adjustable stop mechanism needs to be provided to variably limit the inward stroke of the compensating plunger 24, and for this purpose I secure to plunger 24, at 32, a lever 33 which is provided at its outer end with a roller 34 adapted to engage an adjustable stop 35, said stop being adjustably mounted in an arm 36 carried by a bracket 37. Lever 33 is provided with an intermediate slot 38 into which is projected a pivot pin 39 carried by an arm 40. Pin 39 is also projected into a slot 41 formed in bracket 37, said slot lying at an angle which is substantially coincident with the angular position of lever 33 and its slot 38 when piston 24 is in its outermost position so that, in this position there may be a shifting of pin 39 without producing any swinging movement of the lever 33. Arm 40 is carried by an eccentric strap 43 mounted upon an eccentric 44 carried by a rock shaft 45, which may be rocked by suitable connections 46 with a speed controlled governor 47.

With the parts adjusted as shown in the drawing, the operation is as follows:—With the displacing plunger 13 at the end of its outward, or suction, stroke, compensating plunger 24 has been driven inward by the pressure within chamber 27 until roller 34 engages head 35 and as this movement of plunger 24 has been co-extensive, in displacement volume, with the withdrawal of plunger 13, there will have been no flow of material from supply pipe 18 into chamber 11 and consequently, when plunger 13 is projected into the pump chamber 11, plunger 24 will be driven out of the chamber 11, by the pressure exerted by plunger 13, until the end of plunger 25 engages stop 31 which will not be until plunger 13 has reached the inner end of its stroke. Consequently there will be no discharge through pipe 21. During all of this time the only pressure, beyond the mere weight of lever 33, upon pivot 39, was during the time when wheel 31 was in engagement with stop 35 and amounted to not more than twice the total pressure exerted upon the inner end of plunger 25, which, of course, need not be great. By shifting pin 39 to the left, roller 34 will be caused to engage stop 35, and thus prevent

further inward movement of plunger 24, before plunger 13 has finished its outward stroke. Consequently a quantity of liquid will be drawn into the pump, more or less depending upon the differences in volume movement of the two plungers and, upon the return or inward stroke of the displacing plunger 13, plunger 24 will be driven outwardly to its stop before plunger 13 will have finished its inward stroke and there will be a consequent discharge of liquid from the pump. It will be noticed that, by this arrangement, no definite proportion between the displacement volume of the two 15 plungers 13 and 24 need be provided because the inward movement of the compensating plunger is a yielding movement which merely follows the outward movement of the plunger 13 and therefore can at no time exceed, in volume, the volume withdrawal of the plunger 13. On the return or inward stroke of plunger 13 the compensating plunger 24 is forced outwardly, volume for 20 volume, by the plunger 13, until the positive stop 31 is reached.

By this construction, it will be apparent, that I have succeeded in avoiding a difficulty which has heretofore existed in pumps of this general type where, because of a positive connection between the displacing plunger and compensating plunger, very great care had to be exercised in accurately proportioning the two plungers.

I claim as my invention:

1. The combination with a pump chamber, of a displacing plunger projectable into and out of the pump chamber, a compensating plunger projectable into and out of the pump chamber, a stop arranged to limit the outward movement of the compensating plunger, means, independent of the displacing plunger, for driving the compensating plunger inwardly, stop mechanism associated with the compensating plunger for limiting the inward movement thereof, and means by which said last mentioned stop mechanism may be adjusted to variably limit the inward movement of the compensating plunger.

2. The combination with a pump chamber having inlet and outlet valves, of a displacing plunger projectable into and out of the pump chamber, a compensating plunger projectable into and out of the pump chamber, a stop arranged to limit the outward movement of the compensating plunger, means, independent of the displacing plunger, for driving the compensating plunger inwardly, stop mechanism associated with the compensating plunger for limiting the inward movement thereof, and means by which said last mentioned stop mechanism may be adjusted to variably limit the inward movement of the compensating plunger.

3. The combination with a pump chamber, of a displacing plunger projectable into and out of the pump chamber, a compensating plunger projectable into and out of the pump chamber, a stop arranged to limit the outward movement of the compensating plunger, means, independent of the displacing plunger, for yieldingly driving the compensating plunger inwardly, stop mechanism associated with the compensating plunger for limiting the inward movement thereof, and means by which said last mentioned stop mechanism may be adjusted to variably limit the inward movement of the compensating plunger.

4. The combination with a pump chamber having inlet and outlet valves, of a displacing plunger projectable into and out of the pump chamber, a compensating plunger projectable into and out of the pump chamber, a stop arranged to limit the outward movement of the compensating plunger, means, independent of the displacing plunger, for yieldingly driving the compensating plunger inwardly, stop mechanism associated with the compensating plunger for limiting the inward movement thereof, and means by which said last mentioned stop mechanism may be adjusted to variably limit the inward movement of the compensating plunger.

5. In a pump, the combination with a pump chamber, of a displacing plunger projectable into and out of said chamber, a compensating plunger projectable into and out of the chamber, means, independent of the displacing plunger, for driving the compensating plunger inwardly, a stop for uniformly limiting the outward movement of the compensating plunger, a lever connected at one end to the compensating plunger, a stop arranged to engage said lever, a fulcrum for said lever, and means for shifting said fulcrum relative to the lever to vary the relation between said lever and its stop.

6. In a pump, the combination with a pump chamber, of a displacing plunger projectable into and out of said chamber, a compensating plunger projectable into and out of the chamber, means, independent of the displacing plunger, for yieldingly driving the compensating plunger inwardly, a stop for uniformly limiting the outward movement of the compensating plunger, a lever connected at one end to the compensating plunger, a stop arranged to engage said lever, a fulcrum for said lever, and means for shifting said fulcrum relative to the lever to vary the relation between said lever and its stop.

7. In a pump, the combination with a pump chamber, of a displacing plunger projectable into and out of said chamber, a compensating plunger projectable into and out of the chamber, means, independent of the

- displacing plunger, for driving the compensating plunger inwardly, a stop for uniformly limiting the outward movement of the compensating plunger, a lever connected 5 at one end to the compensating plunger, a stop arranged to engage said lever, a fulcrum for said lever, and means for shifting said fulcrum to vary the relation between the lever and its stop.
- 10 8. In a pump, the combination with a pump chamber, of a displacing plunger projectable into and out of said chamber, a compensating plunger projectable into and out of the chamber, means, independent of 15 the displacing plunger, for yieldingly driving the compensating plunger inwardly, a stop for uniformly limiting the outward movement of the compensating plunger, a lever connected at one end to the compensating 20 plunger, a stop arranged to engage said lever, a fulcrum for said lever, and means for shifting said fulcrum to vary the relation between the lever and its stop.
9. In a pump, the combination with a 25 pump chamber, of a displacing plunger projectable into and out of said chamber, a compensating plunger also projectable into and out of said chamber, a pressure plunger and its pressure chamber associated with said 30 compensating plunger to yieldingly drive said compensating plunger inwardly, a stop for uniformly limiting the outward movement of the compensating plunger, and means associated with the compensating 35 plunger for variably limiting its inward movement.
10. In a pump, the combination with a pump chamber, of a displacing plunger projectable into and out of said chamber, a compensating plunger also projectable into and out of said chamber, a pressure plunger and its pressure chamber associated with said compensating plunger to yieldingly drive said compensating plunger inwardly, a stop for uniformly limiting the outward movement of the compensating plunger, a lever connected at one end with the compensating member, a stop arranged in the path of movement of said lever to limit the inward movement of the compensating plunger, a fulcrum for said lever and means for shifting said fulcrum to vary the relation between said lever and its stop. 40
11. In a pump, the combination with a pump chamber, of a displacing plunger projectable into and out of said chamber, a compensating plunger also projectable into and out of said chamber, a pressure plunger and its pressure chamber associated with said compensating plunger to yieldingly drive said compensating plunger inwardly, a stop for uniformly limiting the outward movement of the compensating plunger, a lever connected at one end with the compensating member, a stop arranged in the path of movement of said lever to limit the inward movement of the compensating plunger, a fulcrum for said lever and means for shifting said fulcrum to vary the relation between said lever and its stop. 45
